UNITED STATES PATENT OFFICE.

P FRANK CLARKIN, OF PONTIAC, MICHIGAN.

DESIGN FOR A FENCE-STAY.

SPECIFICATION forming part of Design No. 32,068, dated January 2, 1900.

Application filed November 27, 1899. Serial No. 738,484. Term of patent 7 years.

To all whom it may concern:

Be it known that I, P FRANK CLARKIN, a citizen of the United States, residing at Pontiac, in the county of Oakland and State of Michigan, have invented a new and original Design for a Fence-Stay, of which the following is a specification, reference being had therein to the accompanying drawings, in which—

A represents one member of the fence-stay, which, as shown, extends in a straight line, and B designates the complementary member connected to the straight member, the two members terminating at their connected ends in a straight loop C in alinement with the straight member. The complementary member comprises a plurality of spaced loops D, extending laterally beyond one side of the straight member, and a number of curved

portions E, connecting the loops and each projecting beyond the opposite side of the straight member, as shown.

The leading feature of the design is the straight member terminating at one end in a straight alining loop and having projecting beyond one side a multiple of spaced lateral loops and from the opposite side curved intermediate portions connecting the loops, as shown.

What I claim as my invention is—

The design for a fence-stay substantially as herein shown and described.

In testimony whereof I affix my signature in presence of two witnesses.

P FRANK CLARKIN.
